UNITED STATES PATENT OFFICE.

JAMES C. DAWSON, OF WEBSTER GROVES, MISSOURI.

LOOSE-LEAF BINDER.

1,077,682.

Specification of Letters Patent.

Patented Nov. 4, 1913.

Application filed November 11, 1912. Serial No. 730,699.

To all whom it may concern:

Be it known that I, JAMES C. DAWSON, a citizen of the United States, and resident of Webster Groves, county of St. Louis, 5 and State of Missouri, have invented certain new and useful Improvements in Loose-Leaf Binders, of which the following is a specification, and which are illustrated in the accompanying drawings, forming a part 10 thereof.

The invention relates to loose leaf binders and more particularly to those of that type having filing posts of arch form arranged along one edge of a suitable base and rising 15 therefrom.

The object of the invention is to provide a binder of the type described having improved means for supporting the filing posts to permit the arches to be opened and closed. 20 A detail of the invention provides improved means for positively holding the sheets in adjusted position in the binder when shiftable sheets are used therein.

In the accompanying drawings—Figure 1 25 is a perspective view showing a binder embodying the features of improvement provided by the invention, the parts of the binder mechanism being illustrated in open position; Fig. 2 is a sectional plan view 30 of the same, the principal plane of the section being indicated by the line 2—2 on Fig. 3, and some of the parts being broken away to a lower plane; Fig. 3 is a longitudinal sectional view of the binder taken on the line 3—3 of Fig. 2.

A base plate of the form usually provided in binders of the general type to which the present invention relates is shown at 10 in the drawings. This base plate together with a suitable top plate 11 serve as covers for the sheets 12. Preferably the base plate 10 is rabbeted along one edge, as shown at 27, to receive the base member 26 of the binder mechanism. In this instance, the base member 26 of the binder mechanism takes the form of a flattened housing having closed ends, and is secured to the base plate 10 within the rabbet 27 by set screws shown at 14.

60 A plurality of pairs of filing posts, as 15, 16 and 17, 18, are provided for receiving the sheets 12. The posts of each of these pairs are normally connected at their higher ends, as by means of arches shown at 31 and 32. Each of these arches is most desirably formed integral with one of the posts, as 16,

18, of the corresponding pair. A firm connection with the other post, as 15, 17, is provided by forming a stud, as 33, 34, upon the free end of each of the arches 31, 32 and by providing a socket, as 35, 36, in the higher end of the corresponding post 15, 17 for receiving such stud. The sheets 12 have slotted apertures, as 21 and 22, to enable them to run upon the binder post as also to be shifted in position thereon in a direction parallel to the plane of the sheet. They are also provided with other apertures, as 23, 24, for receiving additional posts designed to hold the sheets in adjusted position. When sheets of this form are to be used in the binder, an additional pair of posts, shown at 19, 20, are preferably provided for entering the apertures 23, 24 of the sheets. These posts are shown as being uniform in height with the posts 15, 17, and they are unconnected. The posts 15, 17 and 19 are shown as being rigidly mounted in and rising from the upper wall of the tubular base member 26. The posts 16, 18 and 20 each extend through a slotted aperture, as 30, in the upper wall of the tubular base member 26 and are rigidly secured at their lower ends to a plate 29 housed within the chamber of the base member. As shown, 85 the plate 29 is provided with trunnions 37, 38 at its opposite ends. A slotted bearing block 39 is rigidly fixed within the chamber of the base member 26 for receiving each of the trunnions 37, 38. The plate 29 is accordingly adapted for a vertical reciprocating and a swinging movement, such as is required for raising and lowering the posts 16, 18 to bring the studs 33, 34 into and out of engagement with the sockets 35, 36 and 90 for swinging these posts into and out of parallel relation with the posts 15, 17. As sheets engaged with the posts 16, 18 will also be engaged with the posts 20, it is desirable that all of these posts should be 100 moved together, and it is for that reason that the post 20 is mounted in the plate 29.

A locking plate 40 is mounted within the chamber of the tubular base member 26 for holding the plate 29 against movement when the posts which are carried by the plate are in closed position. As shown, the movement of the locking plate 40 is guided and limited by means of a pair of studs 43 each of which is rigidly mounted within the 110 chamber of the tubular base member 26 and passes through a slotted aperture 41 in the

locking plate. The plate 29 and the locking plate 40 are each provided with lateral extensions, those of the plate 29 being shown at 42, 44, and those on the locking plate 40 being shown at 45, 46. These lateral extensions are so arranged upon the two plates that by longitudinal movement of the locking plate 40 its lateral extensions 45, 46 may be moved over the lateral extensions 42, 44 of the plate 20 to hold the latter plate against movement.

Preferably a key-operated mechanism is provided for longitudinally reciprocating the locking plate 40. As shown, a screw-threaded plunger 47, having one of its ends, as 51, formed for the reception of a key (not shown), is employed. The other end of the plunger 47 has swiveled engagement with the plate 40. This swiveled engagement is constructed by forming a T head 49 upon the inner end of the plunger 47 and by providing a T shaped socket 50 in the adjacent end of the plate 40 for receiving the T head of the plunger. The plunger 47 has screw-threaded engagement with a bearing block 48 rigidly mounted within the chamber of the tubular base member 26, and a keyhole 52 is formed in the end wall of the base member in line with the plunger.

In the use of the binder with sheets of the form shown, the filing arches comprising the two pairs of posts 15, 16 and 17, 18 will normally be locked in closed position by the engagement of the lateral extensions 45, 46 of the locking plate 40 with the lateral extensions 42, 44 of the plate 29. When it is desired to differentiate any one of the sheets 12 from other sheets, as when a new entry has been made, the sheet to be so differentiated will be raised on the posts 15, 17 and 19 until it becomes disengaged from the post 19. The sheet may then be shifted to cause one of its edges to project beyond the corresponding edges of other sheets in the manner indicated at 53. When the sheet is again lowered the post 19 will enter a different one of the apertures 23, 24 than the one with which it was formerly engaged. This post will accordingly serve to positively hold the sheet in the adjusted position. When any number of sheets are transferred to the other side of the binder, they will be-

come threaded onto the post 20 in the same relative relation as when they were engaged with the post 19, and this post will then serve to positively hold them in adjusted position.

For the insertion or removal of sheets the arches will be opened as appears in Fig. 1 and also by dotted lines in Fig. 3. For this purpose a key (not shown) is applied to the end of the plunger 47 through the key opening 52 and the plunger rotated to shift the locking plate 40. The plate 29 being now free to be moved upwardly as well as rocked upon the trunnions 37, 38, the posts 16 are raised to lift the studs 33, 34 out of engagement with the sockets 35, 36, and are then swung to an inclined position. For closing the binder the posts 16, 18 are moved to cause the studs 33, 34 to be hooked into the sockets 35, 36, and the plunger 47 is reversely rotated by the key to move the locking plate 40 over the lateral extensions 42, 44 of the plate 29. When the plate 29 is locked in this manner, the arches are as rigid as if in one piece and there is but one joint in each arch over which the sheets must be passed in transferring them from one side of the binder to the other.

I claim as my invention:

1. In a loose leaf binder, in combination a plurality of pairs of filing posts, one of the posts of each pair being fixed and the other post of each pair being movable toward and away from the fixed post, all of the movable posts being rigidly connected, and the posts of one pair being of such length as to meet when the movable posts are in one position, the posts of another pair being separated at all times.

2. In a loose leaf binder, in combination, two pairs of relatively movable filing posts, the corresponding posts of the two pairs being rigidly connected, the posts of one pair being of such length as to meet when in one position and the posts of the other pair being separated at all times.

JAMES C. DAWSON.
